DOUBLE ACTING CHURN

Raleigh C. Moore, McKinney, Tex.

Application May 14, 1935, Serial No. 21,470

1 Claim. (Cl. 259—57)

This invention relates to an improved butter churn and more particularly to a novel and improved structure of a so-called duplex or dual type wherein substantially duplicate cream charged containers are mounted in a suitable rotary carrier in such a manner to counteract one another so as to oppose each other with equal force to provide a desired counterbalancing action.

10 It has been discovered that by coordinating a pair of simultaneously rotatable frames in such a manner as to provide holders for the churning containers and by counterpoising the containers to assume positions at right angles to each other 15 and filling said containers with equal amounts of cream they coact in unison when set in rotation to work in opposition and when associated with a suitable source of power and a support provide for uniform continuity of rotation to equalize 20 stress and strain and to minimize the power required to operate such improved double-acting churn structure.

The foregoing comprehends in a general structural way the developments to be hereinafter described, though it may be introduced here that other features and advantages, especially of a specifically structural nature, will become more readily apparent from the complementary illustrative drawings and the explanatory descriptive 30 matter.

In the drawings:

Figure 1 is an elevational view of the complete machine or structure developed in accordance with the principles of the present inventive conception.

Figure 2 is an end view, that is a view looking at Figure 1 in a direction from left to right.

Referring now to the drawings by distinguishing reference numerals it will be observed that 3 denotes the base. This comprises a pair of suitable risers or rests 4 with a board superimposed thereon to serve as a platform 5 for the electric motor. Incidentally this motor 6 constitutes the preferred source of power but it is evident that 40 the machine may be either hand operated or controlled by an engine or any appropriate prime mover. The motor is here shown as having its shaft equipped with a pulley 7 to drive a belt 8 trained over a larger pulley 9 on a shaft carrying 45 a pinion 10. The shaft 10 is supported on an upright or standard 11 whose upper end is apertured to provide a suitable bearing. There is a complementary upright 12 on the opposite side of the structure which has its upper end apertured to 50 provide a similar bearing. The numeral 13 design-

nates a horizontal brace rod extending through the intermediate portions of the uprights and 14 represents a V-shaped brace whose crotch portion is fastened as at 15 to the intermediate part of the board or platform 5, the arms being fastened 5 as at 16 to the end portions of the brace rod 13. This provides for rigidity and stability in the frame structure which constitutes the support for the double-acting rotary carrier. This rotary carrier is made up of a pair of substantially rectangular companion frames 17 and 18 fastened together in positions at right angles to each other and provided with suitable trunnions 19 and 20 mounted for rotation in the bearings in the upper ends of the uprights. The trunnion 19 is provided with a relatively large power take-off gear 21 which is in mesh with the pinion 10 whereby to rotate the two frames 17 and 18 in unison. These frames obviously serve as holders for the jars or other containers 22 for the cream to be 20 churned. Inasmuch as each frame structure is the same in construction I will describe but one. It may be said that one end bar 23 of the frame is provided with right angularly disposed arms 24 having upturned ends 25. These features serve 25 to accommodate the cruciform rests for the bottoms of the jars. Each cruciform rest comprises the members 26 and 27 cooperating with the features 23 and 24. As a general proposition the frame is made of metal and the cruciform rests 30 or adapters are wood to provide the desired cushioning properties for the bottom of the jars 22. The opposed end bar 28 of the frame is provided with a thumb screw 29 carrying a lid 30 to serve as an effective cover for the neck of the jar. The 35 numeral 31 is merely a pet cock or vent to relieve gas pressure which is sometimes built up in the jar during the churning operation.

Importance is attached to the arm formation at one end of the frame which serves to accommodate the cushioning cruciform adapters which function as rests to accommodate the glass jars. The clamping lid and retaining means at the opposite end of the frame also possess their proportionate share of merit. It follows, therefore, that 40 these features, particularly the rotary frame unit as a carrier for the jars, have been carefully selected and mechanically coordinated to promote smooth and dependable operation due to the compensating and counterbalancing factors, whereby 45 to render the structure devoid of jerky operation with the result that proportionately less power is needed for effective control and well-balanced 50 operation.

It is thought that persons skilled in the art to 55

which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice, if desired.

10. Having thus described the invention, what is claimed as new is:

As a component part of a structural assemblage of the class described, a rotary counter-balanced carrier unit for a churning vessel including a substantially rectangular frame, a closing lid attached by an adjusting screw to one end member of the frame, the opposite end member being provided with centrally disposed outstanding arms, and a cruciform adapter device attached to said last named end of the frame and associated with said arms. 5

RALEIGH C. MOORE.
